(57) **CLAIM**

The ornamental design for an extendable blind, as shown and described.

DESCRIPTION

FIG. 1 is a front perspective view of an extendable blind showing our new design in a collapsed configuration and with a sheet attached thereto;

FIG. 2 is a top perspective view of the extendable blind of FIG. 1, shown with the sheet removed;

FIG. 3 is a top plan view of the extendable blind of FIG. 2; FIG. 4 is a front perspective view of the extendable blind of FIG. 2;

FIG. 5 is a bottom plan view of the extendable blind of FIG. 2;

FIG. 6 is another front perspective view of the extendable blind of FIG. 1, shown in an extended configuration and with a sheet attached thereto;

FIG. 7 is a top perspective view of the extendable blind of FIG. 6, shown with the sheet removed;

FIG. 8 is a top plan view of the extendable blind of FIG. 7; FIG. 9 is a front perspective view of the extendable blind of FIG. 7; and,

FIG. 10 is a bottom plan view of the extendable blind of FIG. 7.

In the drawings, portions of the extendable blind shown in broken lines form no part of the claimed design.
